UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

CONNECTER FOR DEMOUNTABLE AUTOMOBILE DOORS.

Application filed June 27, 1923. Serial No. 648,095.

To all whom it may concern:

Be it known that I, MATTHEW R. HULL, a citizen of the United States, residing at Connerville, in the county of Fayette and 5 State of Indiana, have invented certain new and useful Improvements in Connecters for Demountable Automobile Doors, of which the following is a specification.

My said invention relates to a connector 10 for demountable automobile doors and it is an object of the same to provide improved means for holding the upper part of the door tightly closed.

Another object is to provide a connector 15 which shall be readily demountable together with the upper door section.

Referring to the accompanying drawings, which are made a part hereof and on which similar reference characters indicate similar 20 parts,

Figure 1 is a perspective of my improved device,

Figure 2, a section on line 2—2 of Figure 1,

25 Figure 3, a detail of a post shown in Figure 1, and

Figure 4 a detail of a bracket shown in Figure 1.

In the drawings reference character 10 indicates a permanent lower door of an automobile which may be of any conventional or preferred form and has mounted thereon an upper door section with upper and lower window sections 12 and 13, the 25 upper section being slidably mounted in guides 14 and any convenient means being provided for holding it in raised position when desired.

The guides are formed on a frame 15 extending about the opening of the upper door section, this frame being usually made of wood and having a metal frame 16 secured to the front thereof.

The side members of the frame have secured thereto near their lower ends bent strips of sheet metal 17 forming holding means for the bent ends 18 of a rod which is the principal element of the connector between the door sections. Said rod has 50 horizontal body portions 19 which are parallel to the upper part of the door and are connected at one end by an intermediate section comprising parts 20 bent at right angles to the parts 19 and extending across 55 the thickness of the lower section, vertical

parts 21 and a horizontal connecting part 22 at the lower end of the vertical parts 21.

The lower permanent section has sockets 23 adapted to receive posts 24 provided at their upper ends with eyes embracing the 60 respective body portions 19 of the connector. The part 22 is held in place by means of a bracket comprising two plates 25 and 26. The rear section 25 of the bracket is permanently secured to the permanent door by 65 screws 27 and the part or plate 26 which at its upper end has a rounded part 28 extending over the plate 25 is secured to said plate by means of screws 29 after the connector has been positioned relatively to the first-named plate. The plates 25 and 26 are bent at their lower ends as shown in Figure 4 to receive the part 22 of the connector and hold the same in place.

The connector is formed of resilient material and the various parts are bent in such a manner that under normal conditions the upper door section is tilted slightly toward the body of the car so that the extreme upper edge strikes first in closing the door and 70 when the door is fully closed the parts of the connector are under strain. This strain is borne mainly by the body portions 19 which are twisted as the door closes and the short connecting parts between said body 75 portions and the vertical parts 17 which are bent at the same time.

In positioning the removable door section on the permanent door it will be seen that all that is necessary is to introduce the posts 90 24 into their sockets and to locate the part 22 as indicated after which the plate 26 is fixed in place. In removing the upper door section the screws 29 are taken out and the plate 26 can then be removed after which 95 the entire upper door section can be lifted off together with the connector.

It will be obvious to those skilled in the art that my invention may be modified in various ways without departing from the 100 spirit of the invention and therefore I do not limit myself to what is shown in the drawings and described in the specification, but only as indicated in the appended claims.

Having thus fully described my said invention, what I claim as new and desire to secure by Letters Patent, is:

1. A supporting bracket for demountable automobile doors comprising a rod having 110

- an intermediate portion for attachment to the permanent door section of an automobile said rod having a portion extending upward and transversely of said door from each end 5 of said intermediate portion with upward extensions for attachment to the demountable door section, and supporting elements on the transverse portions of the rod adapted to fit in sockets in the permanent door 10 section, substantially as set forth.
2. In a door, a permanent lower section, a demountable upper section, a resilient connector having bent ends for securing it to the demountable section, horizontal parts 15 lying close to the demountable section and an intermediate bight extending to the inner edge of the permanent section and then down along the inner face of the same, and means for securing the bight to the permanent door section, substantially as set forth.
3. In a door, a permanent lower section, a demountable upper section, a resilient connector having bent ends for securing it to the demountable section, horizontal parts 20 25 lying close to the demountable section, and an intermediate bight extending to the inner edge of the permanent section and then down along the inner face of the same, a bracket comprising a plate to be secured to the permanent door section, and a curved end thereon extending over the lowermost 30 part of said bight, substantially as set forth.

4. In a vehicle door, a permanent lower section, a removable upper section, a connector secured at its ends to the upper section said connector having a horizontal portion lying against the inner face of the permanent section and a bracket for holding the said horizontal portion comprising a plate permanently secured to the permanent 40 door section, a plate removably secured to the permanent plate, and means on said plates for gripping the adjacent part of the connector, substantially as set forth.

5. A supporting bracket for demountable 45 automobile doors comprising a rod having an intermediate portion for attachment to the permanent door section of an automobile said rod having a portion extending upward and transversely of said door from each end 50 of said intermediate portion with upward extensions for attachment to the demountable door section, and means loosely mounted on the transverse sections adapted to be secured to the permanent door sections, substantially as set forth.

In witness whereof, I have hereunto set my hand and seal at Connersville, Indiana, this 25th day of June, A. D. nineteen hundred and twenty-three.

MATTHEW R. HULL. [L. S.]
